UNITED STATES PATENT OFFICE.

HENRY W. ROUNTREE, OF RICHMOND, VIRGINIA.

TRUNK.

SPECIFICATION forming part of Letters Patent No. 399,439, dated March 12, 1889.

Application filed December 21, 1888. Serial No. 294,341. (No model.)

To all whom it may concern:

Be it known that I, HENRY W. ROUNTREE, of Richmond, in the county of Henrico and State of Virginia, have invented a new and useful Improvement in Trunks, of which the following is a specification.

My invention is in the nature of an improvement in trunks designed to give access to the bottom of the trunk without the necessity of lifting the tray out of the trunk; and to that end it consists in the peculiar construction and arrangement of the tray and its supports in the trunk, whereby the tray may be slid back on a horizontal line into the hinged lid or top when open without lifting the tray off its supporting-strips, as will be hereinafter fully described.

Figure 1 is a vertical transverse section of the trunk with its cover raised or open and the tray slid back. Fig. 2 is a modification of the tray.

A is the body of the trunk, and B its hinged cover, which may be of any approved pattern or material.

C is a supporting-strip for the tray, one of which is arranged at each end of the trunk, near the upper edge of the same. The rear edge of the trunk at a is cut down or reduced in height a little, so as to leave this edge a little below the upper surface of the supporting-strips C, so as to be out of the way of the tray when slid back. On the upper surface of these strips C are arranged anti-friction rollers b.

D D' represent the tray, which is made, preferably, in two sections hinged together at the top by hinge c. This tray rests upon the anti-friction rollers, and when the lid of the trunk is raised and thrown back and access is desired to the bottom of the trunk the tray is simply slid back on a horizontal plane without being lifted, and if the space thus opened is not large enough the front section, D, of the tray is thrown back on its hinges over the section D', as shown in dotted lines, which gives free access to the bottom of the trunk to remove any large article that may be contained in the trunk.

If it is desired to have the tray set lower in the trunk, the supporting-strips C may be fixed to the trunk at lower levels, and instead of cutting down the back edge of the trunk at a the rear lower portion of the tray may be cut away or formed with a recess, d, on its under side, as in Fig. 2, so that only the top portion of the tray protrudes into the lid of the trunk when forced back.

In making use of my invention the lid of the trunk is simply raised and the tray forced straight back into the same without raising it, and in closing the trunk the folding of the lid forward forces the tray to its place without having to touch the tray at all.

Having thus described my invention, what I claim as new is—

1. The combination, with a trunk, its hinged lid or cover, and supporting-strips for the tray fixed to the ends of the trunk, of a tray sustained upon these strips and adapted to slide horizontally back on said supports so as to protrude into the hinged cover, substantially as described.

2. The combination, with a trunk, its hinged lid or cover, and supporting-strips for the tray fixed to the ends of the trunk, of a tray sustained upon these strips and made in two hinged sections and adapted to slide horizontally back on said supports so as to protrude into the hinged cover, substantially as described.

3. The combination of the trunk having its rear edge, a, cut down or reduced in height, the supporting end strips, C, having their upper edge higher than the rear edges of the trunk, and provided with anti-friction rollers, and the tray made in two hinged sections and arranged upon the rollers on the strips to slide horizontally back into the lid of the trunk when raised.

HENRY W. ROUNTREE.
